(57) **CLAIM**

The ornamental design for a portion of a display screen with a set of avatars, as shown and described.

DESCRIPTION

FIG. 1 is a front view of an avatar from a set of avatars, shown in isolation, showing our new design;

FIG. 2 is a front view of a second avatar from the set of avatars, shown in isolation;

FIG. 3 is a front view of a third avatar from the set of avatars, shown in isolation;

FIG. 4 is a front view of a fourth avatar from the set of avatars, shown in isolation;

FIG. 5 is a front view of a fifth avatar from the set of avatars, shown in isolation;

FIG. 6 is a front view of a sixth avatar from the set of avatars, shown in isolation;

FIG. 7 is a front view of a seventh avatar from the set of avatars, shown in isolation;

FIG. 8 is a front view of an eighth avatar from the set of avatars, shown in isolation; and,

FIG. 9 is a front view of a ninth avatar from the set of avatars, shown in isolation.

The claimed design is directed to the collective appearance of the set of avatars shown in FIGS. 1-9. The set of avatars shown in FIGS. 1-9 are arranged relatively on the drawing sheet for the convenience of illustration, and the placement of each avatar relative to another, or to the drawing sheet, forms no part of the claimed design.

The outer perimeter shown in dashed broken lines in FIGS. 1-9 illustrates a portion of a display screen that forms no part of the claimed design. The dashed broken lines elsewhere in the figures also form no part of the claimed design.
